UNITED STATES PATENT OFFICE.

WILLIAM KLINE, OF WOODSTOCK, VIRGINIA, ASSIGNOR OF ONE-HALF TO WILLIAM J. MOORE, OF WASHINGTON, DISTRICT OF COLUMBIA.

TYPE-WRITER ERASING DEVICE.

1,108,994.

Specification of Letters Patent.

Patented Sept. 1, 1914.

Application filed June 26, 1913. Serial No. 775,977.

To all whom it may concern:

Be it known that I, WILLIAM KLINE, of Woodstock, in the county of Shenandoah, and in the State of Virginia, have invented 5 a certain new and useful Improvement in Type-Writer Erasing Devices, and do hereby declare that the following is a full, clear, and exact description thereof.

My invention relates to erasing devices 10 forming part of, or being an attachment to a typewriting machine, by means of which the erasure of printed characters may be effected while the paper is still upon the platen, so that changes or corrections can 15 be easily and expeditiously made. A device for this purpose, to be acceptable, must involve no interference with the use of the typewriting machine, nor require any alteration or modification of the machine 20 structure; and it must be easy and convenient of use or manipulation and of doing the work desired quickly and efficiently, and the object of my invention is to provide 25 an erasing device possessing these qualities and others which will appear hereinafter.

In the accompanying drawings—Figure 1 is a vertical section from front to rear of a typewriting machine equipped with an embodiment of my invention, the device being 30 shown in position for an erasing operation, but only a fragment of the typewriting machine being shown; Fig. 2 is a top plan view thereof, but a portion of the typewriting machine being shown; Fig. 3 is a view 35 in vertical section of my erasing device shown separated from the typewriting machine and on a larger scale than Fig. 1; Fig. 4 is a detail vertical section on the line 4—4 of Fig. 3; Fig. 5 is a detail vertical section taken on a different plane than 40 Fig. 4; Fig. 5^a is a detail view on an enlarged scale showing the rotary eraser pivoting means; Fig. 6 is a detail cross section on the line 6—6 of Fig. 3; Fig. 7 is a detail view in section on the line 7—7 of Fig. 4.

The typewriting machine, to which the embodiment of my invention illustrated in the drawings has been adapted, is of the 50 visible writing type, and it needs only a general description, especially since, as I have already explained, no modification or alteration of the typewriting machine is required with my invention since, indeed,

one of its objects is to avoid the necessity 55 of alteration or modification of the typewriting machine structure. It is, therefore, sufficient to say of the typewriting machine shown that it has a frame 10 and a roller platen 11, these parts being mentioned in 60 particular to facilitate the description of the mounting and operation of the erasing device.

Generally described, my erasing device 65 comprises in its preferable form a rotatable disk of rubber, means for rotating the disk while in contact with the paper on the platen and a jointed support for the parts mentioned by which the same may be moved into and out of position for an erasing operation, while supported with such stiffness 70 or rigidity from the machine frame as will enable the action of the disk eraser only on the character it is desired to erase.

It will be understood that my invention 75 may be embodied in a form permitting of its rigid attachment to typewriting machines already made as by the use of a suitable clamping device for the attachment of the support to a part of the machine frame, or the latter, if preferred, may be provided in its original construction with such frame member as may be necessary for the mounting of the eraser mechanism upon the machine. The embodiment of my invention 80 illustrated in the drawings is one in the form of an attachment for machines constructed without reference to the employment of my erasing mechanism therewith.

The jointed support comprises a post 12 standing vertically at the rear of the typewriting machines to the lower frame bar of which it is rigidly clamped as hereinafter described, and an arm 13 which is pivotally 95 connected to the post 12 at the top thereof so that it may be swung to a horizontal position in which it extends forwardly over the top of the typewriting machine above and forward of the platen 11, which is the 100 position when an erasing operation is to be performed or swung to a vertical position so as to place the erasing mechanism entirely out of the way when it is not to be used. The post and the swinging arm are 105 preferably constructed of square tubing because such tubing is light and is strong and may be obtained as stock material and lends

itself readily in various ways to the construction and uses of the parts of the mechanism.

Secured to what is the underside of the pivoted arm 13, when in a horizontal position, is a bracket 14 having a transverse pin 15 on which is pivoted one end of an arm 16 whose other end has a pivotal support for the eraser which is preferably in the form 10 of a disk 17 of rubber. As I prefer to construct it the pivotal support for the eraser is formed by a horizontal pin or stud 18 and a bushing 19 free to turn on the stud, said bushing being divided, or split, and having 15 an opposing pair of axially extending lips 20 separated by a slight space. The bushing 19, preferably has an inner sleeve 180 which has contact with the pivot pin or stud 18 and forms the bearing, as best shown in 20 Fig. 5^a, the bushing and sleeve being fastened together so that they rotate together as one piece, and they are prevented from endwise movement off the pin or stud 18 by a securing pin 181 which passes through the 25 stud 18 and overlaps the end of the sleeve 180. The eraser disk, or rubber, has upon each of its sides a metal wear plate 21 and perforating the plates and disk at the center is a round hole with a radial offset making a 30 key hole slot 22 which fits the bushing, and as the opposite sides of the radial slot are engaged by the bushing lips with some pressure, due to the tendency of said lips to spring outward when the eraser disk is 35 slipped upon the bushing, the eraser disk is thereby firmly held upon the bushing although the disk may be readily removed and replaced as by a new disk when this may be desired on account of the reduction 40 of diameter of the eraser disk from use. The pivot-forming stud and bushing are supported only at one end so that an eraser disk may be readily applied and removed.

An advantage of the non-circular form 45 of the bushing pivot which results from the presence of the radial lips, is that only an eraser disk provided with the complementary hole can be used so that I am thus able to control or make sure that the disks supplied for use in the mechanism shall be proper or suitable to be used.

In the underside of the swinging arm 13 just above the eraser disk, is a slot or opening 23 through which the upper portion of 50 said disk is adapted to project and be in contact with the underside of a sliding or reciprocating rod or bar 25 which is supported by said arm so that by the sliding movement of said rod, and preferably its 55 inward movement and the frictional contact thereof with the periphery of the disk, the latter may be rotated or turned for an erasing operation as hereinafter described. At its inner end the slide rod 25 bears against 60 one end of the coil spring 26 whose other

end bears against a cross piece or partition 27 in the arm near its pivot or hinge, said spring being placed around the rod 28, which, at one end is attached to said partition and passes through an opening in the 70 end of the push rod 25 (which is made hollow for the purpose). Said rod 28 has a head 29 that snugly fits the interior of the push rod so that thus a steady guiding means for the push rod is supplied by said 75 rod 28, while additionally to brace or support the push rod from lateral movements it closely fits a guide opening in the outer end wall 30 of the arm 14, and at its inner end has a clip form bearing member 31 that 80 engages the inner surface of the top and sides of the arm 14. The spring 26 acts normally to move the push rod outward so that the movement of the push rod to rotate the eraser disk is inward and against 85 the pressure of the spring and for conveniently pressing or moving it against the pressure of the spring it has on its outer end a head 32. Adjacent the head 32 the rod has an annular groove 31 for engagement by a spring latch 33 secured to the outer side of the arm 13 and thereby the push rod is latched in a position where it is practically wholly contained within the 90 arm 13 so that it is out of the way when the 95 eraser is not to be used. For convenient lifting of the latch 33 to free the push rod, it has at its outer end a cross bar 34, and the outer ends of said cross bar are adapted 100 to be engaged by the tips of the first and second fingers of the hand when the thumb is applied to the head on the push rod to force it inward and thus the hand is supported and steadied against any sidewise tendency 105 which might tend to vibrate the eraser supporting arm 13 laterally and interfere with a clean operation of the eraser upon a single character to be erased. The spring latch 33 is attached at its inner end to the top of 110 the tube 13 by a clip 330 that straddles the tube 13 and is secured thereto by screws 331, which, at their inner ends project sufficiently into the tube to form stops for engagement by the bearing member 31 to limit the outward movement of the push rod 25 under 115 the outward pressure of its spring 26.

Pivoted to a horizontal pin 35 that passes through the bracket 14, is a strap or plate 36 which has a curved portion that is concave on its underside and which is curved on an 120 arc of a radius the same as the radius of the arc of the platen roller against which said plate is adapted to bear during an erasing operation. Said plate 36 has a limited up and down swinging motion, its upward 125 motion being caused when it is pressed against the platen and said upward motion is provided so that, by means of a spring 38 which is placed under tension by such action of the plate the eraser disk will be moved 130

with sufficient pressure against the push rod 24 as to produce the friction between the rod and the disk required for the efficient revolution or turning of the eraser disk for an erasing operation by that portion of the disk which is in contact with the paper on the platen. The spring 38 is coiled around the pivot 15 of the arm which carries the eraser disk, one end bearing against the underside 5 of said arm and the other end bearing against the plate 36 which by its upward movement tightens the coils of the spring, and hence, causes the end of the spring which bears against said arm to swing the 10 arm upward. The plate 36 is extended by a reversed curve beyond the point where it needs bear against the platen so as to form a housing, and in furtherance of this purpose there is attached to each side of said 15 plate a side plate 39 which extends sufficiently high as always to overlap the sides of the arm 13 and thus at all times, except when access to the rubber disk is required, the mechanism below the arm 13 is housed. 20 For the protrusion of that portion of the eraser disk which is necessary to give it contact with the paper on the platen, the curved plate 36 has a slot 40. Each of the side members or plates 39 of the housing has a 25 forwardly extending lug or tongue 41 which is engaged by a lip or flange 42 on a catch 43 slidably mounted on the outer end of the arm 13. When it is desired to release the 30 housing and permit it to be swung to a position to completely expose the eraser disk, as when a worn disk is to be replaced by a new one, such catch is moved outward to clear the tongues on the housing side plates. The spring latch 33 which is provided to hold 35 the push rod 24 at its inner limit of movement is also utilized to hold the housing latch at its inner position, said spring latch 40 being provided for this purpose with a downwardly projecting stop or lug 44. 45 The portion of the disk rotating rod 25 which engages the periphery of the disk has the form of a groove 45 on the underside of said disk rotating rod 25 so that there are downwardly projecting flanges that overlap 50 the opposite sides of the disk at the periphery thereof and thereby afford a lateral support for the disk at its rim that prevents any wabbling motion thereof and assures that in wearing away the periphery of the 55 disk will be a smooth regular surface in good condition for an erasing operation.

An important advantage from the mounting of the eraser disk on a movable support, such as the swinging arm 16, is that notwithstanding the decrease in diameter of the disk in consequence of its use it is always in proper operating engagement with the push rod so that substantial reduction of the diameter of the disk may take place before 60 it requires to be discarded or thrown away.

Unequal wear of the eraser disk, which might result in an eccentric formation thereof, is obviated by the employment of the loose friction connection between the disk rotating rod and the disk, because after the 70 disk has been rotated forward for an erasing operation the pressure may be released so that upon the return stroke of the push rod under the action of the return spring it will cause no reverse rotation of the disk, or at 75 best only a slight rotation thereof.

The post 12, as I prefer to construct it, comprises two telescopic members or sections, each of square tubing, the hinge connection between the swinging arm 13 and the post being formed at the upper end of the inner post section 46, the upper end of said inner post section being straddled or embraced by ears on the arm 13, which in turn are overlapped by ears on the upper 80 end of a short vertical tube section 47 which telescopes over the upper end of the vertical post section 48, a pivot bolt or screw 49 being passed through the described overlapping portions of the post section and the 85 swinging arm 13. Thus a stiff rigid support is provided at and contiguous to the joint between the post and the swinging arm 13 which precludes any such lateral movement of said swinging arm as would prevent limiting the erasing action to a particular character and result in rubbing adjacent printed characters.

To prevent loosening of the pivot 49 (which is in the form of a screw or bolt), 100 from the swinging of the arm 13, various expedients may be resorted to. Thus, as shown in the drawings, the pivot bolt or screw may be passed through a bushing 50 against whose ends the screw head and the 105 securing nut abut, and a lock nut may be employed.

The post sections 46 and 48 are detachably connected by a spring latch 51 secured to the outer side of the post section 48 which has a pin passing through a hole in the side of the post section and enters a hole in the side of the inner post section 46. Thus when desired the swinging eraser-carrying arm 13, along with the inner post section 46, 110 may be removed from the typewriting machine.

At its lower end the outer post section is attached to a frame that comprises a horizontal base 52 that extends equal distances 115 on opposite sides of the post, and an upwardly and inwardly inclined brace 53 that reaches from the outer end of the base to the contiguous side of the post section 48, the two upwardly and inwardly extending braces thus formed being rigidly attached at their upper ends to the post on opposite sides thereof and thus a rigid support is provided for the post at its lower portion 120 that eliminates any lateral movement that 125

130

would be objectionable to the satisfactory operation of the eraser. Increased stiffness is imparted by extending a bent portion of the base up into the post section 48. At its lower end a bolt 54 is provided that passes through said inwardly extending portion of the base and the contiguous sides of the post section 48 and through vertical portions of the braces 53 and a lug 55 on the outer side of each of said vertical portions, which lug projects rearwardly from a plate 56 which is rigidly clamped to the rear bar of the machine frame by overhanging lugs 57 and clamping screws 58. A limited swing of the post 12 backward and forward is desirable to enable the eraser disk to be brought into proper working relation with the paper on the platen, and the bolt 54 arranged as described provides the necessary pivotal connection for this purpose. To limit the outward or rearward swing of the post, a suitable stop is provided which may consist of a headed projection or screw 59 attached to the clamp plate 56, and a screw 25 or stud 60 secured to one of the braces 53 and projecting so that it will encounter the head of the screw 59.

When it is desired to erase a character from the paper on the platen, the spring 30 latch 33 is lifted to free the push rod 25 so that the latter is moved by the action of its spring to its outermost position and the arm 13 is swung downward and forward to bring the eraser disk to the platen, the latter having been partially rotated to bring the line with the character to be erased sufficiently above the printing point of the machine to give access of the eraser disk thereto. With the fingers bearing upon the outer end of the arm 13 and caught over the handle of the latch 33, and the thumb bearing against the head upon the outer end of the push rod, a slight downward pressure of the fingers will, due to the bearing of the curved plate 26 upon the platen, result in increasing the tension of the spring 38, and the friction of the disk and the push rod 25, so that upon an inward movement of the push rod by the thumb the eraser disk will be rotated and the portion of the periphery thereof in contact with the character on the paper which it is desired to erase, will rapidly pass over said character and remove it, the work being done quickly and thoroughly and limited to the character it is desired to erase. If there are carbon sheets, each sheet in succession after the original may be similarly operated on, it being necessary merely to rock the swinging arm 13 to carry it and the erasing mechanism out of the way for turning over each sheet after it has been acted upon and swinging the arm back again in position for use on the succeeding sheets. It is very important that an erasing device should be adaptable for erasers on the

carbon sheets, and I have accordingly met this requirement in making my invention.

It will be understood that though the details of construction that appear in the embodiment of my invention which I show in the drawings and have described, are useful, and in some case important, in that particular embodiment, said details of construction may be varied from in other embodiments of my invention, and hence, I do not restrict the scope of my protection thereto.

Having thus described my invention what I claim is—

1. In an erasing mechanism for typewriting machines, the combination of a rotatable eraser, a support upon which it is freely rotatable, and eraser-rotating means acting directly upon the eraser and moving cross-wise of the eraser axis. 80

2. In an erasing mechanism for typewriting machines, the combination of a rotatable eraser, eraser-rotating means acting directly upon the eraser, said means consisting of a reciprocating slide, and a support 90 for the eraser and its operating means movably attached to the typewriting machine whereby the eraser may be placed in and removed from position for use.

3. In an erasing mechanism for typewriting machines, the combination of a rotatable eraser disk, a support upon which the disk is freely rotatable, and means for rotating the same acting directly upon the periphery of said disk and having frictional contact with the disk and being free therefrom. 95

4. In an erasing mechanism for typewriting machines, the combination of a rotatable eraser disk, and a slidable rod having frictional contact with the disk. 105

5. In an erasing mechanism for typewriting machines, the combination of a rotatable eraser disk, means for rotating the same acting directly upon the periphery of said disk, said disk being supported for movement toward and from said rotating means. 110

6. In an erasing mechanism for typewriting machines, the combination of a rotatable eraser disk, and means for rotating the same 115 acting directly upon the periphery of said disk, said disk being supported for movement toward and from said rotating means, and a spring acting upon the disk support.

7. In an erasing mechanism for typewriting machines, the combination of a movable supporting member mounted on the typewriting machine, an eraser disk, an arm carrying said disk movably connected with said supporting member, disk rotating means 125 mounted in said member directly engaging the disk, a spring acting on the disk-carrying arm, and a platen engaging plate movably connected with said supporting member having contact with said spring. 130

8. In an erasing mechanism for typewriting machines, the combination of an eraser disk, means for rotating the same, said means comprising a disk-engaging slide, and a pivot upon which said disk is mounted to revolve, the disk being removably mounted upon said pivot.

9. In an erasing mechanism for typewriting machines, the combination of an eraser disk, means for rotating the disk, having frictional contact directly with the disk, and a pivot for the disk upon which it is detachably mounted having a radial projection, the disk having an opening corresponding to the configuration of the pivot.

10. In an erasing mechanism for typewriting machines, the combination of a jointed support comprising a post rigidly attached to the machine frame at the rear side thereof, and an arm pivoted to the free end of the post to swing to and from position for use, and eraser mechanism carried by said arm.

11. In an erasing mechanism for typewriting machines, the combination of a jointed support comprising a post attached to the machine frame, and an arm swinging to and from position for use, an eraser carried by said arm, and an eraser operating slide mounted in said arm.

12. In an erasing mechanism for type-

writing machines, the combination of a jointed support comprising a post attached to the machine frame, and an arm swinging to and from position for use, an eraser carried by said arm, an eraser operating slide bar mounted in said arm, a spring for moving said slide bar in one direction, and a latch for said slide bar to hold it against the action of said spring.

13. In an erasing mechanism for typewriting machines, the combination of a rotatable eraser disk, a support upon which it is freely rotatable, and a reciprocating disk rotating bar having a grooved portion to engage the periphery of the disk.

14. In an erasing mechanism for typewriting machines, the combination of a jointed support comprising a post at the rear of the machine, and an arm pivoted to the top of the post and swinging backward and forward, an erasing mechanism carried by said arm, and a post-supporting means allowing limited backward and forward movement of said jointed support.

In testimony that I claim the foregoing I have hereunto set my hand.

WILLIAM KLINE.
